IRONING MACHINE

Frederic B. Clark, Englewood, N. J.

Application January 11, 1940, Serial No. 313,312

3 Claims. (Cl. 38—9)

This invention relates to an ironing machine and particularly to a flatwork ironer of the type at present widely used in large laundries.

In this type of flatwork ironer, there is a steam chest assembly provided with cradle-like depressions extending across the assembly transversely with respect to the direction of movement of the goods being ironed. There are also ironing rolls disposed above and registering with the said depressions. These rolls are provided with padding for pressing the goods against the ironing surface of the depressions. The goods to be ironed are normally delivered wet to the ironer, direct from the centrifugal wringers, the ironing operation dries the goods.

Heretofore, it has been considered that drying is accomplished largely by absorption of water vapor into the permeable padding of the ironing rolls during the pressing of it against the goods and subsequent escape of this vapor during the remainder of one cycle of rotation of the rolls. It was, therefore, considered necessary to have a large number of rolls, ordinarily six to eight, under which the goods to be ironed are passed in succession in order to obtain adequate drying. In fact the rolls conventionally are placed about as close together above the steam chest assembly as feasible mechanically. The use of such a number of rolls involves not only a large expense for initial equipment (usually about a thousand dollars per roll contained in the complete assembly), but also additional operating and maintenance expense.

I have now found that I can obtain drying that is substantially equal to or better than that obtained with the usual number of rolls, by reducing the number of rolls to approximately half or slightly more, provided I do not decrease greatly the area of the upper surface of the chest.

My invention, briefly stated, comprises an ironer in which the space of a large part of the steam chest ordinarily overlaid by rolls is exposed directly to the atmosphere, thus reducing the number of rolls and eliminating the depressions corresponding to the eliminated rolls.

The invention resides substantially in the combination, construction, arrangement and relative location of the parts of the machine described herein and will be illustrated by description in connection with the attached drawing to which reference is made.

Fig. 1 is a vertical sectional view of my ironer.

Fig. 2 is a plan view of the ironer.

Fig. 3 is an enlarged section of a roll and padding assembly therearound.

Certain parts of the drawing are diagrammatic. Parts not shown or features not illustrated are conventional.

There is shown the steam chest assembly 1, ordinarily of cast iron, provided with an upper ironing surface of smooth metal. The upper part of the steam chest is provided also with the usual spaced transversely extending cradle-like depressions 2. Steam is admitted to the chest in 5 any usual manner to give therein a conventional ironing temperature, say about 310 to 320° F. The chest may be made in sections each of one depression and intermediate parts, the several sections being assembled end to end, to give the 10 construction shown.

Mounted in usual manner above and registering with the depressions are the ironing rolls 3 usually of steel or semi-steel which are driven, as, for example, through the sprockets 4, in the 15 direction shown by the arrows.

Disposed around the several ironing rolls is an ironing pad assembly including a cloth 5 constituting a binder layer directly in contact with the roll, a resiliently yieldable felt or mat 6 and a 20 cover cloth 7 of cotton, wool, or the like.

Tapes 8 pass over the guide rollers 9 and 10 and under the ironing rolls.

Between the depressions 2, the upper or ironing surface of the steam chest rises rather steeply 25 in curvilinear manner as shown, to give upstanding intermediate portions 11 which rise preferably to a level at least a third to a half the distance from the plane of the bottoms of the depressions 2 to the plane of the tops of the rolls 3. This said rise serves not only to make the 30 goods passing thereover more accessible to circulating air, but also increases the distance of travel of the exposed goods.

The goods to be ironed are fed in usual manner, to the right between the steam chest and the roller at the right in Fig. 1. The movement of the rolls 3 moves the goods over and against the ironing surface of the cradles of the steam chest. For flat goods in the form of relatively 40 small pieces such as towels, additional means are provided to move the goods continuously through the machine. These additional means include suitably the driven rollers 12 which rest to advantage upon the crests of the intermediate portions of the chest between the cradles. It is not necessary that these rollers 12 be heated or covered. However, it is desirable that these rollers be bare and that they be geared, through 45 members 13, 14, and 15, to move slightly faster peripherally than the rolls 3. With this arrangement 50

ment, the goods are smoothed on their upper side as they pass over the crests of the steam chest assembly. They may rest upon the tapes, by gravity. I prefer them of three to six inch diameter. Means such as the chain 13 and the sprockets 14 and 15 suitably proportioned make the peripheral speeds of rollers 12 and rolls 3 those desired. I have found little interference of the rollers 12 with the rate of drying when they are small, say of diameter not more than half and suitably a third to a fourth the diameter of the rolls 3.

The tapes 8 of usual type strip the goods from the said rolls and rollers and hold the goods upon the steam chest at positions not overlain by the rolls or rollers. The goods are delivered from the ironer in the direction of the arrow at the left of Fig. 1.

When the ironing rolls are spaced a sufficient distance apart, I may use four of the rolls in place of eight normally used in a flatwork ironer, the rolls being about equally spaced, the steam chest being made to bulge upwardly at positions between the rolls, and the steam chest being of length, from left to right in Figs. 1 and 2, approximately the same as previously used for eight rolls.

With four rolls I obtain drying which is satisfactory and as rapid as with the use of eight rolls in the conventional ironers.

However, if this result is to be obtained with the smaller number of rolls, it is necessary that the width of the spaces between adjacent rolls be greatly increased. Thus, it is necessary that the ironing rolls 3 at their portions nearest to each other be spaced by a distance about one and a quarter times the diameter of the rolls. For some purposes this distance should be increased to one and one-half to twice the diameter of the rolls. Using, for instance, rolls 3 of 12-inch diameter to the number of 4, in the machine shown in Figs. 1 and 2, the rolls are spaced on 32 inch centers. This gives a space of twenty inches between the nearest portions of 12-inch rollers. In another example, 16 inch rolls are spaced at their nearest portions at a distance of twenty-four to thirty-two inches, which means that the rolls are on 40 to 48 inch centers. These diameters of the rolls include the padding. Without the padding the diameters are about half an inch less than stated.

In place of the set of four rolls disposed as shown with respect to the steam chest, there may be used for some purposes a flatwork ironer including only three rolls. In such a case the rolls are spaced as described above and register with three cradle-like depressions, the chest being made sufficiently long to accommodate the rollers and provide the intermediate spaces, with feed and delivery ends arranged as shown in Figs. 1 and 2. Such a 3-roll ironer has practically the same drying capacity per hour as the conventional and more expensive 6-roll ironer of the same over-all length of steam chest as my 3-roll machine.

While the invention is not limited to any theory of explanation of the results obtained, it is my theory that drying of the goods being ironed is caused largely by vaporization of water from the goods directly into the air, and not by vaporization through the permeable packing of

the ironing rolls as previously believed. If my theory is correct, the drying rate will not vary directly with the number of ironing rolls, and such lack of direct relationship has been found to be the case.

The exposure of the goods to the air in passing over the increased exposed surface of the steam chest in my machine is at least as effective as the expensively accomplished additional distance of travel under the permeable padding of the ironing rolls of machines used heretofore.

It will be understood that the details given are for the purpose of illustration, not restriction, and that variations within the spirit of the invention are intended to be included within the scope of the appended claims.

What I claim is:

1. A flatwork ironer comprising a steam chest assembly provided with an upper ironing surface and with spaced transversely extending cradle-like depressions therein, portions of the chest of curvilinear cross section extending upwardly between the depressions, ironing rolls disposed above and registering with the said depressions, padding disposed over the rolls and normally contacting with the chest, means for passing goods to be ironed between the ironing surface and the said padding, and small driven rollers disposed between the said rolls and above the said portions for moving the goods over the said portions, the ironing rolls being spaced apart at their nearest portions at a distance at least one and a quarter times the diameter of the padded rolls and being of the order of at least twice the diameter of the said small rollers.

2. A flatwork ironer comprising a steam chest assembly provided with an upper ironing surface and with spaced transversely extending cradle-like depressions therein, portions of the chest of curvilinear cross section extending upwardly between the depressions, ironing rolls disposed above and registering with the said depressions, padding disposed over the rolls and normally contacting with the chest, means for passing goods to be ironed between the ironing surface and the said padding, tapes extending through the ironer in the direction of movement of the said goods, adapted to rest upon the goods, and to hold the goods upon the ironing surface, small rollers disposed between the said rolls, above the said portions of the steam chest, and resting upon the said tapes, and means for driving the said rolls and rollers.

3. A flatwork ironer comprising a steam chest assembly provided with an upper ironing surface and with spaced transversely extending cradle-like depressions therein, portions of the chest of curvilinear cross section extending upwardly between the depressions, ironing rolls disposed above and registering with the said depressions, padding disposed over the rolls and normally contacting with the chest, means for passing goods to be ironed between the ironing surface and the said padding, small bare rollers disposed between the said rolls and above the said portions of the steam chest, in close proximity thereto, and means for driving the said rolls and rollers, the said means driving the small rollers slightly faster than the said rolls to increase the ironing effect.

FREDERIC B. CLARK.
